UNITED STATES PATENT OFFICE.

CHARLES P. MADSEN, OF CHICAGO, ILLINOIS.

ARMORED CONDUCTOR.

1,247,125.

Specification of Letters Patent. Patented Nov. 20, 1917.

Application filed September 6, 1913. Serial No. 788,487.

To all whom it may concern:

Be it known that I, CHARLES P. MADSEN, a citizen of the United States of America, and a resident of Chicago, county of Cook, 5 and State of Illinois, have invented certain new and useful Improvements in Armored Conductors, of which the following is a specification.

The main objects of this invention are to 10 provide an improved form of armored conductor adapted for high temperature electric heater service, and especially such a conductor adapted to withstand being heated to incandescence and formed to concentrate 15 the delivery of heat; and to provide improved method and means for forming and placing such an armor upon the insulated conductor in the manner specified.

One of the chief difficulties in constructing 20 many types of electrically heated apparatus lies in protecting durably the heat-generating conductor. This difficulty is especially met with in high temperature apparatus in which the heat is transferred 25 from the generating conductor to the work body by radiation or by air convection, as for instance in toasters, broilers, and air heaters. The seriousness of this difficulty is apparent in view of certain conductors 30 now used for heat generating purposes which, even in open air, can be maintained without injury at a temperature much higher than required for the service performed, but which fail when embodied in 35 the types of apparatus commonly in use, with the result that such devices are short lived.

Research and experiment show that the 40 termination of usefulness in the type of apparatus referred to is nearly always caused either by changes due to exposure to the air, or by exterior electrical or mechanical injury to the conductor. The conductors in such apparatus must almost of necessity be the mechanically weakest part of the apparatus, and are therefore peculiarly liable 45 to injury by handling, which the balance of the apparatus withstands.

Moreover, in a high temperature apparatus 50 the conductors are in a condition which renders them abnormally sensitive and susceptible to injury. The heat generation conductors are of high specific resistance, and operate at a high current density. The voltage drop per unit of length is relatively 55 great, and therefore short circuiting or shunting of a portion of the conductor, as

for instance a single turn, causes an abnormally heavy current to pass which injures such conductor at the points of contact. Furthermore, experience has shown that the 60 high heat emissivity rate and the molecular disturbance under which conductors operate, cause the injury to be greater than would otherwise be the case. Thus the effect of a partial short circuit or shunt is likely to 65 be a complete severing of the conductor rather than a mere pitting of the surface.

So great have been these difficulties and so little have they been understood that they 70 have largely prevented high temperature air convection and radiation methods from being extended where such methods would really be most effective.

Attempts have been made to overcome 75 these difficulties by protecting the heat conductor in various ways. No insulating materials or compounds are available which alone possess the required properties. Therefore, attempts have been made to armor the conductors with sheet metal applied mechanically with an insulating medium interposed, but incandescence cannot 80 be maintained with such an armor.

It is difficult in practice to manufacture 85 such an armor which will maintain its shape and remain in solid relation with its contained conductor under the conditions of continual contraction and expansion met with in practice. The resultant looseness in time interposes a considerable temperature 90 lag in the thermal path, thereby reducing both efficiency and speed and also shortening the life of the heat generating conductor by requiring a higher generating rate. Furthermore, such armors are necessarily of 95 considerable mass, which interposes a further resistance and lag in the thermal path.

By this invention I overcome these difficulties by electrically depositing a thin shell 100 of highly refractory metal directly upon and in close contact with a suitably insulated conductor. I find that this method possesses many advantages, some of which are: that an armor of this character is extremely adherent, forming a much more intimate and permanent contact with the insulated conductor than can be obtained by mechanical means; that the shell can be made very much thinner than is possible in a mechanically placed armor; that it is possible to armor 105 much smaller sized heating elements, or groups of conductors, or individual conduc-

tors of much smaller size than is possible where the conductor is armored by mechanical means; and that metals, alloys, or combinations of metals can be thus deposited which are more refractory and better adapted for the purpose than any metal obtainable by mechanical processes.

It is possible to apply this invention in several ways, and I do not wish this invention to be construed as limited to any specific application. To form a heating element a conductor is formed into a unit of any geometric shape desired. It is then insulated in any suitable manner, as for instance with thin porcelain enamel, and a thin electrical deposit of refractory metal is then formed thereon.

The electric deposit may be disposed to armor a heating unit as a whole, or it may be arranged to inclose only individual limbs or members of a unit. Furthermore an extended utility may be obtained by depositing the armoring shell of metal to inclose a metallic or non-metallic supporting member or frame work together with an insulated conductor mounted thereon, in which case the armor serves as a mechanical fastening or binder between the conductor and its supporting frame work, as well as a protection for the conductor.

This process may also be utilized for other purposes than protecting formed heating units. It may for instance be used in the electric heating art for coating or armoring a continuous insulated conductor of indefinite length. Such a conductor is more convenient for forming a radiant type of heating unit of large size or a unit in which the conductor elements are widely spaced. Such a conductor may be made by passing the insulated wire to be armored through a continuously operating plating bath and moving the wire at a definite rate adapted to give the proper thickness of deposit.

Two or more parallel wires insulated from each other in a common mass of insulation may be covered by a single deposited metal armor.

I do not wish this invention to be understood as being limited to a particular metal used in making the armor, nor to a specific process used. I have found, however, that a coating of nickel, or a combination of alloy of nickel and another metal, for example vanadium, are suitable.

In carrying out the process I prefer to use as an insulation a coating of porcelain enamel, fused silica, or a special glass. The outer surface of this insulation is rendered conductive in any suitable way, as for example by applying an adhesive coating and dusting it with a metal powder or plumbago, or by painting it with an aluminum or bronze paint. The unit so treated is then ready for the plating bath.

This invention not only overcomes many of the difficulties heretofore encountered in making radiant types of high temperature heating apparatus, but enables the desirable qualities of radiant construction to be extended in new directions. The importance of this is closely related to the fact that the heat transferring power and efficiency of a heat generating conductor are not directly proportional to its temperature, but to some power of its temperature. With radiant types of construction it is possible to attain a much higher temperature or intensity than is possible in inclosed types, and the speed of operation and efficiency are greater. An illustration of the utilization of this principle is given in one of the drawings herein-after described, which shows a volute heat generating conductor of only a few square inches of incandescent surface capable of doing more work per unit of power input than would be performed by a 6 inch solid disk stove having a surface of about 30 square inches, because with the same power consumption the heat intensity in the former is very much higher, and the efficiency is correspondingly greater.

Several illustrative embodiments of this invention are shown in the accompanying drawings in which—

Fig. 1 is a plan view of a heater element comprising a metallic supporting plate enameled on one side, and having a resistance conductor imbedded in and insulated by the enamel, and an outer shell or armor electrically deposited upon the enamel.

Fig. 2 is a section along the line A—A of Fig. 1.

Fig. 3 is a cross section of a modified form of heater element in which the conductor is wound about the supporting plate instead of disposed upon one side only, and in which the deposited armor completely envelops the element.

Fig. 4 shows a section of armored wire having a thin insulation disposed between the wire and a thin electrically deposited metal covering.

Fig. 5 shows a section of armored twin conductor or twisted pair of wires embedded in insulation and protected by a single shell of deposited armor.

Fig. 6 is a plan view of a heater unit comprising an insulated heat generating conductor arranged in the form of a volute spiral supported on a skeleton frame made up of radiating arms, one-half of the view showing the parts before the armor is deposited thereon and the other half illustrating the completed unit.

Fig. 7 is a vertical cross section along the line A—A of Fig. 6.

Fig. 8 is an enlarged sectional view on the line A—A of Fig. 6.

In the construction shown in Figs. 1 and

2 there is provided a supporting plate or 5 backing member 1 having a coating of suitable insulation 2 on one side, as for instance enamel, and a heat generating resistance member 3 embedded within said insulating material, and a thin outer protective shell or armor 4 consisting of suitable refractory metal electro-deposited upon the insulation as herein described. The said 10 heat generating conductor is provided with broad insulated terminals 5, preferably having perforations 6 adapted to facilitate connection to the electrical circuit. The armor may or may not extend over the back of the 15 plate 1 but the edges should reach back sufficiently to hold the armor securely in place and to supplement its adhesive hold.

In the construction shown in Fig. 3 a central mounting plate 8 is coated with suitable insulation 9 on both sides, the heat generating resistance conductor 10 is disposed about said plate and embedded in said insulating material in the form of a progressive winding whereby the generation of 25 heat is distributed over the whole area of the plate, and an outer shell or armor 11 is deposited upon the foregoing structure in the manner herein specified.

Fig. 4 shows a section of armored wire 30 bent so as to show both a side view and a transverse section, said wire comprising a conductor core 15, a thin layer of insulation 16 thereupon, and an outer casing or protective armor 17 consisting of any suitable 35 refractory metal electro-deposited upon the insulation.

Fig. 5 shows a twisted pair of conductors or wires 18 embedded in and separated by insulating material 19 and an armor 20 electro-deposited upon the insulation.

Figs. 6, 7, and 8 illustrate a special application of armoring on an electric heating unit, showing an extension of the usefulness of such armor for the purpose of 45 mechanically uniting the parts of the supporting frame and the conductors. In the form shown, the frame 25 consists of radial arms 26 made of relatively thin and wide metal strips standing on edge and fastened 50 at their center to a short metal tube or hub 27. These arms are notched as at 28 upon their upper edge to a depth equal to the diameter of the heating wire 29 and its insulation. The thinly insulated heating 55 conductor 29 is shown in the form of a volute spiral, to each end of which is fastened a stud or terminal rod 30. Both studs have insulation continuous with that on the resistance conductor 29. The stud on the 60 outer end of the spiral may be disposed against the side of the adjacent arm 26 where the armor will securely hold it. The inner terminal stud may be held in place in the tube 27 by any suitable means as cement 65 or packing 31. The top of the tube 27 is

notched at 27.1 to receive the end of the conductor leading to the inner stud. All of the non-metallic parts of the structure are rendered conductive on their surfaces, as by a coating of graphite, or a metallizing 70 powder or paint, care being taken to limit the extent of the conductive coating by placing caps of wax or other non-conducting material over the terminals of the conductor to prevent the deposited metal from 75 overlapping the uninsulated parts of the terminals, and thus short-circuiting or grounding the conductor on its armor. It is intended that the insulated wire 29 should tightly fit the notches in the frame. The 80 whole is now ready to be immersed in the electro-depositing bath and receive its metallic coating of integral armor 33.

It is to be understood that any suitable material may be used as a frame or support 85 for holding the heater elements constructed as shown in Figs. 1, 2, and 3 and in Figs. 6, 7, and 8. The armor may be made flexible or rigid according to the quality of metal used and the thickness of the armor required, depending upon the purpose intended. 90

It is further to be understood that whenever the terms "provided with", "fastened to", or "connected" are used in the specification or claims in defining the relation of the conductor to the terminals, these terms are to be construed in their broadest sense and are intended to cover all the usual and well known methods of forming such relations, as, for example, by having the conductor and terminal integral or by otherwise joining them by any well known metal-working or fastening means to effect the desired connection, as shown, for instance, 100 in Fig. 8.

Although several specific embodiments of this invention are shown for clearness of the disclosure of the invention, no attempt has been made to show herein all of the 110 forms and applications of the invention, and it will be understood that numerous details of the constructions shown may be altered or omitted without departing from the spirit of this invention as defined by 115 the following claims.

I claim:

1. A heating unit comprising a conductor, insulating material substantially covering the same, and a closely adherent coating of 120 refractory electrolytically deposited metal forming an armor for said heating unit.

2. A heating unit comprising a conductor, insulating material substantially covering same, and a coating of electrolytically deposited nickel closely adherent to and substantially covering the surface of the insulating material. 125

3. A heating element comprising a conductor, terminals of higher conductivity 130

4 connected to the conductor, insulation substantially covering the conductor and adjacent portion of the terminals, and an armor of electrolytically deposited metal substantially covering the insulated portions of the conductor and terminals.

5 4. A heating element comprising a conductor, terminals of higher conductivity connected to the conductor, insulation substantially covering the conductor and adjacent portions of the terminals, and an armor of electrolytically deposited refractory metal substantially covering the insulated portions of the conductor and terminals.

10 5. A heating element comprising a conductor, terminals of higher conductivity connected to the conductor, insulation substantially covering the conductor and adjacent portions of the terminals, and an armor of electrolytically deposited nickel substantially covering the insulated portions of the conductor and terminals.

15 6. An electric heater comprising a conductor, terminals of greater conductivity connected thereto, a shell of electrolytically deposited metal substantially covering the conductor and a part of the terminals, and a layer of refractory insulation intervening between the conductor and the metal shell and extending beyond the shell upon the surface of the terminals.

20 7. An electric heater comprising a supporting skeleton frame, an insulated conductor arranged thereon in the form of an

35 open grid, said frame being notched to receive said insulated conductor and said frame and said insulated conductor both being covered by an integral closely adherent coating of refractory electrolytic metal.

40 8. An incandescent open work heater of unitary character, comprising an insulated heat generating conductor of open volute spiral shape, in combination with a light metal frame having arms arranged radially and adapted to support said conductor, and 45 an integral close fitting armor of refractory electrolytic metal incasing said frame and conductor and securing the same rigidly together.

49 9. A luminously radiant heat unit, comprising a frame including a vertically disposed hub and a plurality of arms radiating therefrom in a horizontal plane, a spiral conductor mounted on said arms concentrically with said hub, thin refractory insulating material covering said conductor, said arms having notches to receive the insulated conductor at the points of crossing, and a thin integral armor of electrolytic metal covering said conductor and said arms 55 and joining the same rigidly together in a unitary manner.

Signed at Chicago this 4th day of September, 1913.

CHARLES P. MADSEN.
